[57] CLAIM

The ornamental design for a water-bottle, as shown and described.

DESCRIPTION

FIG. 1 is a top perspective view of a water-bottle showing my new design;

FIG. 2 is a front elevational view, the rear view being a mirror image thereof;

FIG. 3 is a side elevational view, the opposite side being a mirror image of the side shown;

FIG. 4 is a top plan view; and

FIG. 5 is a bottom plan view.
